UNITED STATES PATENT OFFICE

EDWARD J. ABBOTT, OF WILTON, NEW HAMPSHIRE

ART OF DYEING FILAMENTOUS TEXTILE SUBSTANCES

Application filed July 10, 1929. Serial No. 377,204.

This invention relates to the art of dyeing filamentous textile substances.

While this art or process is primarily concerned with the treatment of woolen or 5 worsted yarns, slubbings, rovings, sliver, tops, or any other form of elongate fibrous mass in a preliminary or finished state, it is applicable within this invention to vegetable or artificial textiles, which, prior to reaching 10 the state in which it is attempted to dye them, have been dressed, lubricated, or treated with oleaginous materials; or which are oily, gummy, and/or resinous, naturally or artificially, in the state in which it is attempted 15 to dye them. For example, woolen or worsted yarns, slivers, combed tops and many other fibrous aggregates are quite generally treated for working or making them with an oil or an oleaginous suspension, emulsion 20 or solution which may remain in or on the fibers, which may also contain traces of wool fat (lanoline), washing soaps, and many other foreign materials. The presence of these foreign or naturally included materials 25 may be detrimental to even dyeing, especially when it is attempted to dye such materials by pressure circulation through wound or other aggregates or masses. Silk or natural vegetable and synthetic cellulosic fibrous aggregates 30 may in like manner be lubricated or dressed with the same class of materials.

It is in consequence common practice to scour yarns and other filaments or other filamentous aggregates before dyeing, for example 35 with water, ammonia and soap, particularly for the purpose of removing the animal or vegetable oils and other foreign inclusions either natural to the material or added to the material before spinning or other working, as before drawing; it is customary, for instance, to treat combed tops with an emulsion of a suitable oil dispersed in an aqueous menstruum so as to cause the material to retain by capillarity and in uniform 40 distribution about 3% by weight of olive oil or suitable substitute, and also a corresponding quantity of the dispersing, suspending or emulsifying agent, whatever that may be, (usually a soap) and of the water or other liquid in which the oil is dis-

persed. If now the filamentous aggregate or yarn is wound or massed in a package, and it is attempted first to scour and then to dye by pressure circulation through the mass (as by forced circulation through, from within 55 or without, a hollow perforated wound spool or beam, of the wash or dye liquor in the vat or kettle in which the package is immersed), difficulty ensues from the curdled, solid or gelatid product of the oleaginous inclusions 60 and the caustic, ammonia or soap of the scouring liquor; the wound mass of filamentous material, whether a sliver or roving, or yarn, constitutes a quite perfect filter screen or bed, and circulation of liquids for scouring or 65 rinsing inevitably results in deposit of the by-products of scouring on and within one face or the other of the wound mass, depending upon the direction of circulation, and penetrating well into the wound mass. This 70 kind of foreign material so deposited in and on the fibrous material seriously affects dyeing, although I find that a well-distributed small amount of oil of the order of 3% by weight of the fiber, whether in a globular 75 state or in distribution in capillary spaces, offers no considerable obstruction to uniform taking of dye if uniformly distributed.

For the reasons indicated it is difficult practically to scour without leaving deposits from 80 the circulating liquor in the vat or kettle on the wound or compressed fibrous masses, or otherwise fully to remove included oily materials in such a way as to secure that no product of scouring is left on or in the fibrous 85 mass. Solids, gelatid or emulsoid masses resulting from the chemical action of the scouring liquor are inevitably left on one face or the other of or within the wound mass, whether or not the liquor is circulated, and this obstruction on and about the fibers to be dyed is really more harmful to good dyeing than is a well-distributed quantity of dispersed oleaginous matter not washed out.

I have established by experiment that in 95 the case of wool and pressure dyeing by circulation, a slightly acid bath (preferably acetic) before dyeing neutralizes the normal alkalinity of the wool fiber and any other alkaline inclusion resulting from the natural 100

grease or lubricating emulsion with which the wool was originally treated, and that such a slightly acid bath breaks emulsions, coagulates and precipitates the suspended fine particles of oil on the fiber without altering the uniform distribution of these fine particles in the wound mass. Satisfactorily uniform dyeing to the result of a fairly well-distributed deposit of color then results on running in a dye solution into the vat. There is, however, a countervailing objection to this procedure; acidity accelerates the action of the dye, and when the circulation of acid solution is begun even at low temperatures, for example from 70° to 80° F., the filter bed constituted of the wound mass becomes preferentially acid on the side first receiving the circulation, so that when dye solution is afterward run into the circulating current and the temperature increased to a boil for dyeing, the dye preferentially takes more strongly on these previously acidulated fibers, with the result that the part of the wound mass first in contact with the circulating solution takes a darker color in a given time. On attempt to avoid this effect by starting with a neutral or slightly alkaline dye solution and increasing its acidity, I found that I could not avoid freeing into circulation a part of the suspension or emulsion product, or of the oleaginous inclusions, which then deposited on the wound mass as a filter bed when the liquor increased in acidity, and made the dyeing uneven.

I have devised and recommend, in order to eliminate all of these detrimental effects, a procedure characterized by a preliminary treatment for the purpose of breaking suspensions or emulsions in and on the oil-carrying wound masses and fixing the distribution of the oily contents, comprising a preliminary circulation at relatively low temperatures of a salt solution, for example a solution of Glauber's salt ($\text{Na}_2\text{SO}_4 + 10\text{H}_2\text{O}$) or common salt (NaCl). This saline solution has the effect of precipitating or coagulating the oily emulsion in place in a state of fine distribution throughout the wound mass, thus fixing the oil in its original distribution throughout the wound mass, so that there is no emulsion or lather or other gelatinous mass free to circulate with the circulating liquor in the pressure dyeing system, which can possibly be left as a filtrate on one face or the other of the wound mass. Having so treated the oily mass of fiber, a suitable acid, if necessary for the dye process, may then be added slowly during circulation of the saline solution so that it penetrates uniformly through the relatively thick wound mass; the temperature of the circulating liquor may then be raised and the dyestuff be added, with chrome or other mordant if necessary, and the liquor in circulation then raised slowly to a boiling point. The vegetable oil content

of a treating emulsion or any other oily inclusion by this treatment is left in place, and the acidulation of the fibrous mass proceeds evenly without preferential acid concentration anywhere in the fibrous mass, and the dyestuff takes evenly.

An instance of practice will now be described by the aid of the accompanying drawings, in which:

Fig. 1 is a diagram section through a circulating pump and one of a number of wound packages in a dye kettle; and

Fig. 2 is a diagram illustrating the disposition of different solutions adapted to be entered in to the dye kettle.

Referring to Fig. 1, the kettle or vat 1 may be any vessel capable of holding hot liquids, preferably open at the top (although I may employ my process in and for any kind of closed circulating dye system) and having either a steam coil, not shown, or an entrance pipe 2 for live steam as shown for the purpose of heating the contents. The vat 1 may have any desirable devices for circulating its contents, such as a bottom 3 and a false bottom 4 between which is a plenum or suction chamber shown as a plenum chamber 5, through which an induct 6 from vat 1 to a circulating pump 7 may lead. The pump 7 may deliver through pipe 8 into the plenum chamber 5. The false bottom 4 provides seats at 9 for any desired number of spools having perforated tubular barrels 10 which may carry a wound mass of fiber F, which barrels may have any suitable form of sealing head 11 adapted to be held by nut 12 on threaded hold-down bolts 13 attached to the bottom 3 of the vat. With these dispositions, operation of the pump 7 results in penetration of the liquor in the kettle 1 from the inside toward the outside of the wound masses F at pressures dependent upon the rate of the pump 7.

The vat or kettle 1 is provided with a liquid entrance pipe 15, and with a drain pipe 16.

Referring now to Fig. 2, the pipe 15 may communicate with entrance pipes, suitably valved, from supply tanks or other sources of the materials to be used in the process. For example, tank 20 is provided with a solution of a neutral salt, recommended to contain one pound to ten gallons of water of Glauber's salt crystals ($\text{Na}_2\text{SO}_4 + 10\text{H}_2\text{O}$); tank 21 may contain a solution of acetate of ammonia or acetic acid at a suitable and known concentration, and tank 22 may contain a neutral solution of the dyestuff intended to be employed; whereas the tank 23 may be filled with a chrome or any mordant solution. With apparatus so arranged, the procedure is to charge the empty vat 1 with wound beams or spools still retaining the oily emulsion or natural oils or greases; to close the valve of the drain pipe 16, and then

to fill the kettle with a salt solution from tank 20 by suitably manipulating its valve and water supply valve 24 if desired. Tank 20 may be kept at a temperature of 70° F., or the 5 entering solution may be raised to substantially such a temperature by entering steam. The pump 7 is now started. After treatment for a suitable time, for example ten minutes, the valve leading from tank 21 is opened 10 to a degree sufficient to permit, having regard to the concentration of the acid solution, the addition of a normal quantity of acid to the saline solution in circulation during a period of twenty minutes, more or less, whereupon 15 steam is run into the kettle until the temperature reaches about 120° F. Dyestuff is now run into the kettle from tank 22, and the admission of steam continued until the contents of the kettle reaches the boiling point, where- 20 upon after operation under circulation for sixty minutes, or such longer or shorter time as may be desired, all valved entrance pipes are closed, and the spent dye solution run off through the drain pipe 16.

25 The wound masses may then be dried in any usual way, preferably by circulating air under pressure through them.

While I have described a procedure suitable for animal fibers including silk, I am 30 well aware that dyeing vegetable fibers and artificial silk may require dyeing in the presence of an alkaline or neutral liquor, and in that case the contents of the tank 21 will of course be alkaline or no flow from it will be 35 permitted. In some cases brine of common salt may be used from tank 20. So far as I am aware, the neutral saline solution recommended to be used is not detrimental to dyeing in any usual way, whether dyeing is to 40 proceed in an acid or alkaline menstruum; but in case it should be so desired I may modify my process by washing or rinsing after entering the saline solution, and in this case the steps of the process are modified by first 45 circulating a saline solution, then running off the contents through the drain 16, during or before running in water at any desired temperature; circulating the wash water during the drainage at 16 and entrance of more water 50 at the pipe 15, and thereafter closing the drain pipe; then entering an acidulant and a suitable dye solution, or a dye solution of suitable acidity or alkalinity. The beneficial 55 effect of the saline treatment of the included emulsified oil or greasy dressing on the fibrous material is not altered by this washing procedure, which normally is not necessary at all. When dried the wound mass still contains distributed therein substantially the original 60 amount of the applied oil. The presence of a suitable oil, such as olive oil, in the finished product is advantageous to spinning, weaving or knitting, an equivalent dressing quite generally having been supplied after dyeing 65 a scoured textile material.

This process avoids the expense of scouring and the expense of adding oil to the finished dyed product.

I claim:

1. Art of dyeing filamentous textile substances bearing oily inclusions distributed therein or thereon comprising as steps treatment of said substances with a reagent for precipitating in place said inclusions and subsequently dyeing without scouring. 70

2. Art of dyeing filamentous textile substances bearing as an inclusion a vegetable oil dispersed in an aqueous menstruum comprising as a step precipitating in place the oily inclusions by the action of a neutral saline solution in water, and thereafter dyeing the textile substances by circulating through them an aqueous dye solution. 80

3. Art of pressure dyeing aggregate masses of filamentous textile substances bearing an inclusion of an emulsion of an oil dispersed in an aqueous menstruum comprising reacting on the emulsion with a neutral saline solution to precipitate the oily contents on the textile material and thereafter circulating an acid dye liquor through said mass repeatedly. 90

4. Art of dyeing filamentous textile substances bearing as an inclusion a vegetable oil dispersed in an aqueous menstruum comprising as a step precipitating in place the oily inclusions by the action of a solution of Glauber's salt in water, and thereafter dyeing the textile substances by circulating through them an aqueous dye solution. 95

5. Art of pressure dyeing aggregate masses of filamentous textile substances bearing an inclusion of an emulsion of an oil dispersed in an aqueous menstruum comprising reacting on the emulsion with a solution of Glauber's salt to precipitate the oily contents on the textile material and thereafter circulating an acid dye liquor through said mass repeatedly. 105

6. Art of dyeing a wound mass of textile fibers bearing a distributed inclusion of an emulsion of an oil dispersed in a continuous aqueous menstruum comprising as steps acting on the wound mass by circulation therethrough of a saline solution, whereby to fix in place the oily element of said inclusion, and thereafter circulating a dye liquor through the wound mass and drying said wound mass. 110
